UNITED STATES PATENT OFFICE.

ALVIN H. COLBERT, OF CHICAGO, ILLINOIS.

AIR-WASHER STRUCTURE.

Application filed January 22, 1926. Serial No. 84,340.

The objects of this invention are:

First, to provide an improved air scrubber and eliminator structure for the elimination of dirt and liquid in air washers.

5 Second, to provide improved supporting and spacing means for such eliminator plates, and a structure which can be very readily assembled and disassembled in the event of repairs.

10 Third, to provide a special alloy making very stiff non-corrodible plates.

Objects pertaining to details of construction and operation will appear from the detailed description to follow. The invention 15 is defined and pointed out in the claims.

A structure which is a preferred embodiment of my invention is illustrated in the accompanying drawings forming a part of this application, in which:

20 Fig. 1 is a detail perspective view, with a part of the outer casing broken away, of an air washer embodying my improved eliminator plate structure.

25 Fig. 2 is an enlarged detail plan view of the eliminator plate structure, the top spacing and supporting bar structure being omitted.

30 Fig. 3 is a detail end elevational view of the base support for the eliminator plate structure, showing details including the plate supporting bars and spacers.

Fig. 4 is a detail perspective view of one of the eliminator plates in broken section.

35 Fig. 5 is an enlarged detail view of the upper eliminator support cross bar and spacing means and intermediate spacer means.

40 Fig. 6 is an enlarged detail sectional elevational view of the intermediate cross bar and its connection to one of the plates and the spacer, taken on line 6-6 of Fig. 2.

45 Fig. 7 is a detail sectional plan view taken on line 7-7 of Fig. 6, showing details of the connection of the intermediate cross bar to the edge of a spacer plate and of one of the intermediate spacers.

Fig. 8 is a detail perspective view of one of the bottom spacers.

50 The parts will be identified by their numerals of reference, which identify like parts in all the views.

1 is the base casing of an air washer structure. 2 is the upper casing portion. 3 is one of the side panels forming a side of the eliminator structure. 4 is the top plate of the 55 said casing. 5 is the top cross bar U-shaped in form which carries the top spacer bar 6

which is notched at 61 to receive the vertical edges of the eliminator plates and hold them properly spaced. 7 is an end of the cast base enclosed in the lower part of the casing 1, on which rest longitudinal cast cross channel rail supports, on which rest the eliminator plates 10 which are spaced from each other by the spacers 9 which engage in channels 81 in the said rails 8. The spacers 9 are tapered at the top and provided with shoulders 91 and downwardly-projecting lugs or legs 92 which engage the opposite sides of the slot 81 frictionally and are consequently very readily inserted and removed in the assembling of the said plate structure.

The plates are of sheet metal. A special alloy is provided, of lead and antimony 2% to 10% or more which resists the action of water and is comparatively stiff. As the 75 plates are non-corrodible they can be made light. Their edges are double hemmed, as seen at 101, to make a strong supporting rib. The plates have first a straight portion 102, then a slightly deflected portion 103, a 80 reversely deflected portion 104, an increased deflected portion 105, a still more abrupt deflector portion 106, having a special eliminator groove 107, and finishing at the discharge end in a straight vertical portion 108. 85 The vertical rib 101 at that point also assists in elimination.

The upper edges of the eliminator plate are disposed in the slots or notches 61 in the notched bar 6, being secured to the top supporting rail 5 by rivets or bolts 62. Rail 5 is secured by bolts or otherwise. An intermediate support is provided consisting of right angle cross bar 11, secured by bolt 112, the vertical limb of which faces against the 95 edges of the eliminator plate. The horizontal limb extends to the sides of the casing and is held in place by brackets 111 suitably secured to the side panels 3. Certain of the eliminator plates are provided with brackets 12 formed of a strap of metal folded upon itself to form a vertical eye 122 and closed onto the plate and riveted to the plate by rivets 121. A clamp bolt 13 with a projecting finger 131 is disposed in the vertical eye 122 and is drawn down by the screw nut 132 engaging the washer 133 (see Fig. 6), which firmly secures an intermediate portion of the cross bar 11 to the plate structure.

Interposed between the plates are the 110 intermediate spacers 14 which are formed with hook portions 142 to engage over the vertical

limb of the bar 11, the ends of the hook being substantially T-shaped at 141 to extend back of the vertical rib 101 of the eliminator plate, and in the front at 143 to provide complete and effective spacing. These spacers are all retained by friction and may be very readily removed when it is desired to take out any plate.

I have described my improved air washer structure in its preferred form. It can be considerably varied in details without departing from my invention. Steel or other sheet metal plates may be used, and when the plates are of steel the eliminator angle 107 may be omitted. It is not necessary that they be folded in a double hem structure to support the edge. That is desirable particularly with the alloy to which I have referred.

20 Applicant's arrangement of eliminator plates insures a rapid flow of the air and the minimum obstruction in securing elimination. The air enters the eliminator without deflection and coarse particles begin to 25 deposit on the plates. The plate is then deflected slightly at 103, not causing any abrupt interruption of the air and a considerable part of the coarser particles are at once eliminated and the relieved air passes 30 into the more abrupt turn 104 where still further elimination occurs. This is done, successively relieving the air of accumulated moisture, until it passes the last abrupt turn and is delivered straight forward. The 35 elimination is, therefore, as complete as possible with a minimum interruption of the flow of the air.

Having thus described my invention, what I claim as new and desire to secure by Letters Patent, is:

1. In an air washer, a casing, a plate structure comprising vertically disposed eliminator plates, a base with cross bars having longitudinal top grooves thereon, spacers formed with engaging lugs to engage said grooved bars, notched top bars with U-shaped bar means for supporting the same in the top of said casing, an intermediate angle cross bar secured by brackets to the walls of said casing and having its vertical member disposed in proximity to the edge of the eliminator plates and its horizontal member projecting outwardly therefrom, a connecting bracket for one of said plates comprising a sheet metal strap folded upon itself forming an eye at its outer end, a vertical clamp bolt disposed in said eye to clamp and engage the horizontal member of said angle bar, and spacers of hook form to engage over the vertical member of said angle bar and extend between the eliminator plates beyond the edge.

2. In an air washer, a casing, a plate structure comprising vertically disposed eliminator plates, a base with cross bars having longitudinal top grooves thereon, spacers formed with lugs to frictionally engage said longitudinal grooves of said grooved bars, and notched top bars with means for supporting the same in the top of the said casing.

3. In an air washer, a casing, a plate structure comprising vertically disposed eliminator plates, a base, notched top bars with means for supporting the same in the top of the said casing, an intermediate angle cross bar secured by brackets to the walls of the said casing and having its vertical member disposed in proximity to the edge of the eliminator plates and its horizontal member projecting outwardly therefrom, a connecting bracket for one of said plates comprising a sheet metal strap folded upon itself forming an eye at its outer end, a vertical clamp bolt disposed in said eye to clamp and engage the horizontal member of said angle bar, and spacers of hook form to engage over the vertical member of said angle bar and extend between the eliminator plates beyond the edge.

4. In an air washer, a casing, a plate structure comprising vertically disposed eliminator plates, a base, an intermediate angle cross bar secured by brackets to the walls of the said casing and having its vertical member disposed in proximity to the edge of the eliminator plates and its horizontal member projecting outwardly therefrom, a connecting bracket for one of said plates comprising a sheet metal strap folded upon itself forming an eye at its outer end, a vertical clamp bolt disposed in said eye to clamp and engage the horizontal member of said angle bar, and spacers of hook form to engage over the vertical member of said angle bar and extend between the eliminator plates beyond the edge.

5. In an air washer, a casing, a plate structure comprising vertically disposed eliminator plates, a base, an intermediate angle cross bar secured by brackets to the walls of the said casing and having its vertical member disposed in proximity to the edge of the eliminator plates and its horizontal member projecting outwardly therefrom, a connecting bracket for one of said plates comprising a sheet metal strap folded upon itself forming an eye at its outer end, and a vertical clamp bolt disposed in said eye to clamp and engage the horizontal member of said angle bar.

In witness whereof I have hereunto set my hand.

ALVIN H. COLBERT.
